ATTORNEY.

UNITED STATES PATENT OFFICE.

ANDREW SORENSEN, OF OAKLAND, CALIFORNIA.

WASHING MACHINE.

1,423,972.

Specification of Letters Patent. Patented July 25, 1922.

Application filed June 16, 1921. Serial No. 477,966.

To all whom it may concern:

Be it known that I, ANDREW SORENSEN, a citizen of the United States, and resident of Oakland, county of Alameda, and State of California, have invented a new and useful Washing Machine, of which the following is a specification.

The present invention relates to improvements in washing machines and its object is to provide a motor driven washing machine that can be conveniently used in combination with the ordinary wash tray found in most houses, so that water can be run into it directly from the faucets usually provided above the wash trays and the dirty water can be dumped out of the washing machine by merely turning the same upside down, when the water runs into the tray which latter is usually connected with the sewer. A further advantage of my washing machine is that it can be attached to the tray without any difficulty, no tools being necessary, the only fastening means being thumb-screws. Another advantage of my washing machine is that the clothes in the same are washed by the rocking motion of the drum alone and that no agitating means is used inside the drum.

Other objects and advantages of my machine will appear as the specification proceeds.

I show a preferred embodiment of my invention in the accompanying drawing in which Figure 1 represents a top plan view of my washing machine shown in its place in the tray, Figure 2 a side elevation of the same, part of the tray being shown broken away, Figure 3 a cross-section through the same along line 3—3 of Figure 1, Figure 4 an enlarged perspective detail view of one of the bearings for my washing machine, Figure 5 an enlarged perspective detail view of the other bearing for the same, and Figure 6 an enlarged detail view showing the connection between a connecting link and an arm secured to the drum of my washing machine.

Referring to the drawings in detail, it will be seen that the clothes container in my washing machine is a cylindrical drum (1) the ends of which are provided with metal reinforcing members (2) from which extend axial studs (4) adapted to rest in bearings (6). The drum is flattened on top, as shown at 7 and has a preferably rectangular opening in the flat portion which ex-

tends nearly over its whole surface. The opening is flanged and fortified by angle irons (8), one leg (9) of which rests on the rim defining the opening while the other leg (11) toes downward into the drum. Two handles (12) are provided on these angle irons by means of which the drum may be conveniently gripped and rotated or lifted out of the tray (14). The latter is an ordinary wash tray, preferable of concrete, like it is found in most houses, having a drain pipe (16) leading into the sewer and ordinarily provided with hot and cold water faucets. A cover (15) is adapted to fit in the opening of the drum and is provided with a handle (20).

Two bearings (6) are provided in this tray for the washing machine, one at either end. The two are supported on metal members illustrated in Figures 5 and 6. One of them, having the numeral (17), consists of a triangular metal plate (18) having a flange (19) adapted to rest on one of the edges of the tray (14), while the triangular portion extends downward from the flange into the tray along its wall and is firmly held in that position by a thumb-screw (21) which extends through a bracket (22) projecting downwardly from the flange (19) outside the wall of the tray. Small pointed projections (25) allow the plate to grip the wall of the tray and prevent it from sliding. The flange further carries a channel (23) toeing upwardly and disposed transversely to the flange. This channel serves as a support for a motor (24) and its two legs are provided with curved recesses (26) to provide a convenient bed for the motor. The shaft (27) of the motor is adapted to engage, through a clutch mechanism (28), a shaft (29) aligned with the same, which latter shaft is supported in a housing (31) and ends into a worm in the housing. The latter is integrally connected with a housing (32) running transverse to it and supported in a perforated lug (33) rising from the surface of the flange (19). A setscrew (34) firmly holds said housing in its place. In the latter housing is supported the crank shaft (36), one end of which is provided with a worm gear adapted to be engaged by the worm aforesaid while the other end carries the crank arm (37), to the free end of which the connecting rod (38) is pivotally connected as shown at (39). The other end of

the connecting rod pivotally engages an arm (41), Figure 6, which latter rises vertically from one end of the drum, secured preferably to the fortifying metal member (2).

It will be understood that, when the motor begins to work, rotary motion is transmitted to the crank shaft (36) through the worm and the worm gear referred to and this rotary motion transmits rocking motion to the arm (41), which on its hand transfers this rocking motion to the wash drum (1).

To provide some means for adjusting the intensity of the rocking motion of the drum, I secure the arm (41) adjustably to the drum by providing a slot (42) in the arm through which the bolt (43) extends which secures the arm to the drum. If a long rocking stroke is desired, the arm can be let down to the position shown in Figure 2, while when a short stroke is wanted the arm can be raised so that the bottom of the slot (42) shown in dotted lines in Figure 2 comes in contact with the bolt.

Attention is called to the special means shown in Figure 6 for connecting the connecting rod (38) to the arm (41). It will be noticed that instead of the circular bearing ordinarily employed a recess (44) is provided in the underside of the connecting arm. This recess is used for the reception of the bolt (45), Figure 2, which is screwed into the arm (41). To secure the bolt in the recess I provide a latch (46) comprising a metal rod bent to form a right angle, one leg (47) of which is guided underneath the connecting rod through two perforated lugs (48) provided between the end of the connecting rod and the recess so as to just cover the latter, while the other leg (51) extends across the end of the connecting rod and rests in a small groove (52) in the end, when the latch covers the recess (42). Between the two lugs (48) a spring (53) is secured around the leg (47) by a pin (54), which spring prevents the leg from being withdrawn altogether, but allows a withdrawal far enough to open the recess and to allow the bolt (45) to slip out of the same.

It will be seen that in this manner the connecting rod can be connected to the arm (41) very easily and quickly, the only necessary step being a pull on the portion (51) of the latch.

The bearing (6) at the other end is supported in substantially the same manner as the other bearing, without the attachments necessitated by the power arrangement. The detail view in Figure 5 shows the triangular metal plate (56), the flange (57), the bracket (58) and the thumb-screw (59) securing it tightly to the opposite wall of the

tray. The two triangular metal plates (18) and (56) are provided, in corresponding places, with the U-shaped bearing members (61) on which the studs protruding from the drum at either end are rockingly supported.

It will be seen from this description that my washing machine presents a number of desirable features not used before. It may be conveniently used with practically any wash tray in use. To connect it is easy and requires no tools. Place the two bearing members at opposite ends over the walls of the wash tray and secure the drum in the bearings. Engage the connecting rod with the arm (41) by simply snapping the latch, seat the motor so that its shaft engages the clutch mechanism and the machine is ready for use. Open the faucets above the wash tray and allow either hot or cold water to run into the drum. After the washing is done the contents are easily removed from the drum by turning the same half a turn, whereupon the dirty water will flow into the sewer by its own gravity.

I claim:

1. In a motor driven device a pivotally mounted element, a vertical arm secured thereto, a crank shaft mounted transversely to said arm, an operative connection between the crank shaft and the arm whereby a rocking motion is imparted to the latter, a spring latch for establishing and severing said connection and means for rotating the crank shaft.

2. In a motor driven washing machine, an operative connection between the motor and the washing machine comprising two connecting members, a projection on one of said members, a recess in the other member adapted to receive said projection with freedom of rotating motion and a spring-controlled latch for locking the projection in the recess.

3. Means for detachably mounting a wash drum and its agitating means in operative relation to a tray, comprising hanger bearings for the drum detachably secured to the walls of the tray on opposite sides, driving means supported on one of said hanger bearings in operative relation to the drum, and a manually detachable operative connection between the drum and the driving means, comprising a crank shaft associated with the driving means, an arm rigidly secured to the drum, a connecting rod and means for pivotally securing the same between the arms and the drum including a spring latch for allowing of manual engagement and disengagement.

ANDREW SORENSEN.
